Inventor:
John Chitra
By Edward Fay Wilson Attest.

UNITED STATES PATENT OFFICE.

JOHN CHITRA, OF CHICAGO, ILLINOIS.

LAMP SHADE.

Application filed June 20, 1927. Serial No. 199,951.

My invention relates to improvements in lamp shades and has special reference to improvements in methods and means for decorating lamp shades and similar devices.

5 A particular object of my invention is to produce a lamp shade which may be made principally of silk fitted over a suitable frame and to produce suitably colored pictures or designs on the lamp shade, the designs or pictures having an outer or finishing coating of clear glass particles which give the design a most beautiful scintillating appearance and which adds life to an otherwise dead picture.

15 Many of the ideas involved are doubtless useful in the production of other articles besides lamp shades, and these should not be limited to this particular device, though it now appears that the production of ornate lamp shades is the most important object.

20 My invention will be more readily understood by reference to the accompanying drawing forming part of this specification and in which:

25 Fig. 1, is a side elevation of a lamp shade made in accordance with my invention;

30 Fig. 2, is a vertical, central, sectional view on the line 2—2 of Fig. 1;

35 Fig. 3, is a fragmentary plan view of the ornamented portion of one of the panels showing one step of the process of producing the ornament;

40 Fig. 4, is a view similar to Fig. 3, but showing a further step in the production of the ornament;

45 Fig. 5, is a sectional view on the line 5—5 of Fig. 3;

50 Fig. 6, is a sectional view on the line 6—6 of Fig. 4;

55 Fig. 7, is a sectional view similar to Fig. 6, but showing the next step in the production of the ornament; and

60 Fig. 8, is a similar section and shows the last step in the production of the ornament.

In said drawings 1, indicates a lamp shade of a usual coned panelled shape. The shade comprises a wire frame 2, over which a cloth cover 3 is tightly stretched and secured. The cover 3 is preferably of silk and is first made up of suitable size and shape so that when secured upon the frame the panels 4 thereof shall be stretched tightly and held in flat condition.

65 The shade is adapted to be supported upon

a post 5 and to contain electric lamps, not shown. After the cover has been properly secured upon the frame it is ready to be ornamented. The ornamentation is preferably in the form of a picture of flowers, leaves, birds, etc., and I have shown a spray with flowers at 6 on one of the panels 4. This ornament 6 consists of a stem 7, leaves 8 and flowers 9. The stem may be brown, the leaves different shades of green and yellow, and the flowers different shades of pink or red, or any other pleasing combination of colors can be used. In the several figures the conventional indications of colors has been used to indicate the different colors.

70 In producing the ornamentation it has been a most difficult undertaking to produce the ornament in such a manner or by such means that the oils or other ingredients of the paints would not spread beyond the outlines of the ornament and also to color the ornamentation.

75 By proceeding in accordance with my invention I am enabled to produce properly colored ornamentations and without any spreading of the oils beyond the outlines of the ornamentation. I first sketch out the outline 10 of the ornament, as shown in Fig. 3, and then I paint the panel within the outline with a quick drying enamel such as "Duo enamel". This first coat is shown at 11 in Figs. 3 and 5. It is indicated in Fig. 3 by the shade lines which indicate glass. The one essential to this coat is that it shall be so quick drying that it dries before it can spread beyond the surface to which it is applied.

80 Having thus prepared the surface of the silk I can now apply the oil color paints to the several parts of the design, as indicated in Figs. 4 and 6 at 12. Having permitted the oil colors to dry I then proceed to prepare the design to receive the glass particles or beads. For this purpose I coat the ornament with a suitable varnish, as indicated at 13, Figs. 7 and 8, and when this varnish has dried a proper amount so that it becomes quite sticky or tacky, I apply a coating of the glass particles or beads, as shown at 14, Fig. 8. When the varnish is completely dried the ornamentation is finished.

85 90 95 100 105 110 For the purpose of keeping the first coat, enamel, from becoming too hard and tending to crack, it is mixed with a suitable proportion of medium, preferably "gypsy" painting

medium being used, and likewise the paints are also mixed with medium to cause them to spread smoothly and evenly.

So far as I am aware, ornamentation of this character has never heretofore been produced principally on account of the difficulty of applying the oil paints, but by first enamelling the surface with a mixture of enamel and medium I provide a foundation suitable for receiving the oil paints and which foundation, due to the use of the medium, is flexible enough not to crack in use.

As lamp shades are always transparent or translucent it will be understood of course that the materials of which the ornamentations are made are such as will transmit light so that their beauty may be seen both by reflected and transmitted light.

The final result is a most beautiful, colored and glass covered ornament which adds materially to the appearance of the plain silk shades and provides a shade upon which a large business is being built up.

I claim:

1. The herein described method of ornamenting cloth such as silk, for use in lamp shades and the like which consists in outlining a portion of the surface of the cloth to receive the ornamentation, applying enamel mixed with medium to said outlined surface,

applying colored oil paints to the enamel when the enamel has dried, applying varnish to the painted surface and before the varnish is completely dried, applying glass beads to the varnish, thereby producing a suitable ornamental colored design covered with glass beads.

2. A lamp shade or similar article, comprising a translucent fabric such as silk, a frame upon which the fabric is tightly stretched, an ornamentation on the fabric comprising a coating of enamel mixed with medium covering a certain area to represent a selected picture, a layer of colored oil paints on the enamel, a layer of varnish on the oil paints and a layer of glass beads secured by the varnish.

3. A lamp shade comprising a suitable frame of wire, a silk cover stretched and secured upon the frame, an ornamentation on the silk, comprising a coating of enamel mixed with medium covering a certain area to represent a selected picture, a layer of colored oil paints on the enamel, a layer of varnish on the oil paints and a layer of glass beads secured by the varnish.

In testimony whereof, I have hereunto set my hand, this 6th day of June, 1927.

JOHN CHITRA.
